UNITED STATES PATENT OFFICE

AUGUST L. N. FLEMING, OF CARTHAGE, NEW YORK, ASSIGNOR TO SUPERIOR LINKING MACHINE CORPORATION, OF WILMINGTON, DELAWARE, A CORPORATION OF DELAWARE

LINKING MACHINE

Application filed November 19, 1928. Serial No. 320,509.

My invention relates to linking machines of the type shown and described in my co-pending applications Serial No. 187,676, filed April 29th 1927 and Serial No. 307,315, filed 5 Sept. 20th 1928.

This invention relates to twisting or rotating mechanism for dividing sausage casings into links.

One of the objects of my invention is to 10 provide a rotor and twisting mechanism in conjunction with means for clamping a section of a casing in timed relation to a pair of pincers.

Another object of my invention is to 15 construct a housing for a rotor or twisting mechanism operable therein including provision for introducing the casing to be divided into links or sections through the top of the housing to the rotor or twisting mechanism.

20 Another object of my invention is to provide a novel and improved rotor or twisting mechanism having a pair of clamping plates operable in timed relation to a pair of pincers and rotating mechanism.

25 A continued object of my invention is to provide a rotor or twisting mechanism in a linking machine having a pair of intermittently actuated clamping plates and means for regulating the tension or pressure of said plates and operable in timed relation to a pair of pincers and gearing for rotating the twisting mechanism.

To enable others skilled in the art to more 30 fully comprehend the underlying features of my invention, reference is had to the accompanying drawing forming a part of the specification in which.

Fig. 1 is a side view, parts being shown in section.

40 Fig. 2 is a view taken on the line 2—2 of Fig. 1.

Fig. 3 is a view taken on the line 3—3 of Fig. 1.

45 Fig. 4 is a view partly in section showing the rotor or twisting mechanism, with the clamping plates.

Fig. 5 is a view showing the rotor clamping plates and cover plate detached.

50 Referring now to the drawing wherein like reference characters designate corresponding

parts throughout the several views, 5, 6 designates the front and rear wall respectively of a housing which may be fixed to or integral with the base 7. The wall 5 is somewhat curvilinear in shape and the wall 6 slopes toward the top, each of said walls having openings 7. The top of each wall of said casing is provided with an outwardly curved or flared guide 8^a which are spaced apart sufficiently to permit the casing to be introduced through the top to the twisting mechanism or rotor further to be described in detail.

In my copending application, Sr. No. 187,676, above referred to, the stationary and hinged brackets are constructed and arranged for cooperation with each other to open and close, the filled casing being initially positioned for the twisting operation when the hinged bracket is open. It will be noted that the sections of the housing forming the bearing for the bushing and twisting mechanism being open at the top permits of the initial introduction or positioning of the filled casing in the same manner, thus dispensing with the means and mechanism for actuating the hinged bracket.

The housing serves as a bearing for a rotor bushing 8 held in position by a flanged annular plate 8^a, said bushing being open or split as at 9 to coincide with the top opening of the housing. The rotor bushing is provided with gear teeth 10 which mesh with bushing drive gear 11 on a shaft 12. The drive gear 11 meshes with a second drive gear 13 and the gear teeth 10 of the rotor bushing 8 meshes with an interior rotary gear 14 arranged for cooperation with an intermittently actuated mechanism (not shown) for opening and closing an upper pincer 15 and a lower pincer 16 on a pincer shaft 17 at points outside the housing proper and the twisting mechanism. The upper and lower pincers are arranged contiguous to each other and in overlapping relation, the outer end 18 of the upper pincer extending beyond the vertical portion 19 and the V-shaped notch 20 of the lower pincer so that when the pincers are in their closed position, as shown by Fig. 1, the casing will be clamped at the axial center of the rotary bushing.

Inside the bushing, there is provided a pair of opposed, spring tensioned rectangular clamping plates 21, 22, each provided with recesses or openings 23 whereby a firm grip or clamping action may be had on the casing during the rotation or twisting operation and when the pincers are closed. It will also be noted that the clamping plates are slightly bent longitudinally as at 24 at an angle of approximately 165 degrees which also aids in properly clamping and retaining the section of the casing while it is being rotated. Fixed to each clamping plate is a curved lever 25 pivoted to the bushing by pins 26, said levers having a segment of teeth 25^a which are in meshing relation for uniform cooperation to intermittently actuate the clamping plates in engagement with and out of engagement with a section of the casing. One of the clamping plates has attached thereto a bell crank lever 27 which carries at its inner end 28 a short shaft 29 and roller 30. The outer end of the lever 27 is provided with an opening 41 to which is connected the lower end of a tension spring 32, the upper end of said spring being adapted for connection to a clamping spring bracket 33. The bracket is equipped with a series of threaded openings 34 to receive a threaded screw to which the upper end of the spring may be adjustably connected and whereby the tension of the spring may be increased or decreased, as desired. The respective curved levers and bell crank lever are operable through slots or recesses 35, 36 in the bushing, having a cover plate 37 secured by screws 38, said plate having recesses 38^a which also limits the inward movement of the levers and the said clamping plates. The tension spring 32 normally produces an upward pull on the bell crank lever thus maintaining the clamping plates in their operative position and in engagement with the section of the casing to be rotated or twisted. In order to actuate the curved arms and the clamping plates to their inoperative position to release the section of the casing, the roller 30 is adapted to be intermittently engaged by the upper end of a vertical ram 40 movable in guides or bracket 41 of the housing. The ram is provided with a recess or groove 42 adapted to be actuated by the inner rounded end 43 of a lever 44 fulcrumed as at 45. The outer end of the lever is pivoted as at 46 to a curved link 47 which is in turn connected to a lever and link mechanism 48, 49 which are intermittently operable from a driven shaft or other mechanism (not shown). When the lever 44 is rocked on its pivot by the curved link 47 and the connected lever and link mechanism, the ram actuates the roller and the curved arms carrying the clamping plates producing a downward pull on the bell crank lever, expanding the spring 32. When the tension on the spring is again released, the clamping plates are again

brought into play, this operation being effected in intermittent timed relation with the open and closed position of the pincers and the gearing that rotates the bushing.

The operation of the twisting or rotating mechanism will now be clearly understood from the drawing particular attention being directed to Figs. 1 and 4 of the illustration. The sausage casing to be twisted into links is first introduced through the open top of the housing and within the split rotor and on the plate 37 at which moment the pincers outside and at each end of the housing are in their open position and the clamping plates are in their spread or inoperative position, the roller 30 being in engagement with the vertical ram 40. When the casing is thus positioned, the pincers close and the section of the casing between the pincers are held in clamped position by the clamping plates 21, 22 upon the rocking of the lever 44 which lowers the ram and disengages the roller 30. When so held, the rotor or bushing carrying the curved arms and clamping plates are swiftly rotated by the gearing and at a predetermined moment, the ram is again actuated by the lever 44 thus opening or spreading the clamping plates at which time the pincers open, thus permitting the casing to be advanced longitudinally by suitable mechanism (not shown) as described in my said copending application. The pincers, clamping plates and gearing for operating the rotor or bushing are all operated in time relation so that the operation is continuous and automatic.

While I have shown and described my invention with some degree of particularity, it will be realized that other modifications and changes may be resorted to under special conditions. I therefore do not wish to be limited and restricted to the exact details shown and described but reserve the right to make such changes and modifications as may fairly fall within the scope of the subject matter now being claimed.

Having shown and described my invention what I claim as new and desire to secure by Letters Patent is:—

1. In a linking machine having a fixed housing, a rotor within the said housing arranged to receive a section of a filled casing therein, means for clamping the casing outside of the rotor, means for clamping the section of the casing within the rotor and means for revolving said rotor.

2. In a linking machine having a housing, a split rotor within the said housing arranged to receive a section of a filled casing therein, means for clamping the casing outside of the rotor, means for clamping the section of the casing within the rotor and means for revolving said rotor.

3. In a linking machine having an open housing, a split rotor within the said housing

arranged to receive a section of a filled casing therein through the said opening of the housing, means for clamping the casing outside of the rotor, means for clamping the section of the casing within the rotor and means for revolving said rotor.

4. In a linking machine having a housing, a split rotor within the housing arranged to receive a section of a filled casing therein, gear teeth carried by the rotor, said housing forming a bearing for said rotor, means for clamping the casing outside of the rotor, means for clamping the section of the casing within the rotor and means for revolving said rotor.

5. In a linking machine having a housing, a rotor within the said housing arranged to receive a section of a filled casing therein, means for clamping the casing outside of the rotor, means carried by the rotor for intermittently engaging and disengaging the section of the casing between said clamping means and means for revolving said rotor.

6. In a linking machine having a fixed housing, a rotor within the said housing arranged to receive a section of a filled casing therein, gearing for revolving the rotor, means for clamping the casing outside the rotor and means carried by the rotor for intermittently engaging and disengaging the section of the casing between the clamping means.

7. In a linking machine having a fixed housing, a rotor within the housing arranged to receive a section of a filled casing therein, gearing for revolving said rotor, means for clamping the casing outside the rotor, relatively movable clamping plates carried by said rotor and means for intermittently actuating said plates into and out of engagement with the casing.

8. In a linking machine having a fixed housing, a rotor within the housing arranged to receive a section of a filled casing therein, gearing for revolving said rotor, means for clamping the casing outside the rotor, a pair of arms having clamping plates carried by the rotor and means for intermittently actuating said arms.

50 9. In a linking machine having a fixed housing, a rotor within the housing arranged to receive a section of a filled casing therein, gearing for revolving said rotor, means for clamping the casing outside the rotor, a pair of pivoted arms having clamping plates carried by the rotor, meshed segment gears formed with said arms and means for intermittently actuating said arms.

60 10. In a linking machine having a fixed housing, a rotor within the housing arranged to receive a section of a filled casing therein, means for clamping the casing outside the rotor, gearing for revolving said rotor, a pair of relatively movable curved arms having clamping plates for engaging the section

of the casing within the rotor, means for adjusting the tension of the arms, meshed segment teeth formed with said arms and means for intermittently actuating said arms to release the clamping plates from the casing.

70 11. In a linking machine having a fixed housing, a rotor within the housing arranged to receive a section of a filled casing therein, means for clamping the casing outside the rotor, gearing for revolving said rotor, a pair of pivoted arms operable through recesses in the rotor, clamping plates carried by said arms, an adjusting spring for regulating the tension of said clamping plates, meshed segment teeth formed with said arms, a trip arm connected to one of said plates, and means for intermittently engaging said trip arm whereby the clamping plates are released from said casing.

75 12. In a linking machine having a base, a housing formed with said base, a rotor within the housing arranged to receive a section of a filled casing therein, gearing for revolving the rotor, means for clamping the casing, outside the rotor, a pair of clamping plates normally engaging the casing within the rotor, and an intermittently operated ram for disengaging the plates from the casing.

80 85 In testimony whereof I affix my signature. 90
